UNITED STATES PATENT OFFICE.

THOMAS A. DE VILBISS, OF TOLEDO, OHIO, ASSIGNOR TO THE DE VILBISS MANUFACTURING COMPANY, OF TOLEDO, OHIO, A CORPORATION OF OHIO.

CHECK-VALVE.

No. 914,122.

Specification of Letters Patent.

Patented March 2, 1909.

Application filed March 13, 1908. Serial No. 420,813.

To all whom it may concern:

Be it known that I, THOMAS A. DE VILBISS, a citizen of the United States, and a resident of Toledo, in the county of Lucas and State of Ohio, have invented a certain new and useful Check-Valve; and I do hereby declare the following to be a full, clear, and exact description of the invention, such as will enable others skilled in the art 10 to which it appertains to make and use the same, reference being had to the accompanying drawings, and to the figures of reference marked thereon, which form a part of this specification.

15 My invention relates to check-valves, and particularly to the class of valves adapted for use in connection with compression bulbs or the like, but is not restricted to such use.

In the manufacture of this type of valves 20 it has been customary to form one end of the valve plug or holder with spaced prongs or fingers which are bent over to form means for retaining the valve member in its chamber and at the same time allowing the air 25 or water, as the case might be, to pass around the valve and escape from the chamber. Owing to the expense and slowness of manufacture of this form of valve when made of brass or other hard metal, 30 due to the separate operations necessary to form the spaces between the prongs or fingers thereof, they have, as a rule, been cast from lead, which at its best forms valves of crude and unfinished appearance and construction.

The object of my invention is to obviate 35 the objections incident to the manufacture and use of the above form of valve by the provision of a simple and highly efficient 40 valve of this type, which can be cheaply and quickly manufactured of brass or other suitable material and has the retaining means for its valve member formed by a single operation of a suitable stamping die, 45 and which also has its valve retaining means fashioned to provide a more perfect operation and positive seating of the valve than is the case with the forms of valve above described.

50 The operation, construction and arrangement of the parts of my invention are fully described in the following specification, and illustrated in the accompanying drawings, in which,—

55 Figure 1 is a central longitudinal section

of the plug or holder of my invention as it appears before the walls of the valve-chamber are acted upon to form the valve retaining means thereof. Fig. 2 is a side elevation of the plug in completed state. 60 Fig. 3 is an inner end view thereof, and Fig. 4 is a section taken on the line E E in Fig. 3.

Referring to the drawings, 1 designates the plug or holder, which is of suitable form to adapt it to be inserted in an end of a compression bulb or in a tube associated therewith, or with any other suitable means for creating a forced draft therethrough. The plug or holder 1 is provided in one end with the central bore or inlet opening 2 and in its 70 other end with a valve-chamber 3, which has a valve-seat 4 at the inner end of the bore or opening 2 and carries a valve 5 of disk or other suitable form adapted when seated to close the communication between 75 said opening and chamber. The chamber 3 is provided at its outer end with the restricted outlet opening 6, the margin of which is corrugated, as shown at 7, to provide openings or crevices 8 through which 80 the fluid may escape laterally into the outlet opening 6 when the valve is lifted from its seat and held against the inner side of such corrugated portion by the action of the fluid thereon. It will be apparent that the 85 size and shape of the escape openings 8 depends upon the depth and manner of forming of the corrugations.

While the corrugated end of the plug or holder 1 may be formed in any suitable 90 manner, a preferable and very simple method of forming the same consists in first making the chamber 3 cup-shaped in form with its walls tapering to a rather thin edge, as shown in Fig. 1, and then operating on this 95 wall with a suitable tool or die so as to compress it inwardly to provide the restricted outlet opening 6 and form the corrugated margin 7 at a single operation.

It will be apparent that this construction 100 forms a cheap and very efficient form of valve, which is easy and rapid of manufacture; and also that a back pressure of fluid on the valve will be constrained to pass through the restricted central outlet opening 105 6 of the valve-chamber and be applied directly to the central portion of the valve 5, thus tending to hold it more firmly to its seat than is the case with the constructions of valve-casings or plugs heretofore used in 110

which the bending over of the valve retaining prongs or fingers form openings over the edge of the valve.

The drawing in of the valve-chamber wall 5 in the manner described also contracts or shapes that end of the plug in conical form, thus facilitating an insertion thereof in the article with which it is to be associated.

I wish it understood that I do not desire 10 to be restricted to the exact details of construction and arrangement of the parts shown, as obvious modifications will occur to persons skilled in the art.

Having thus described my invention, what 15 I claim as new and desire to secure by Letters Patent, is,—

A check-valve, comprising a metal member having a bore therethrough which is abruptly enlarged at one end to form a valve

chamber having an annular seat at its inner 20 end, said chamber having the outer edge of its wall crimped inwardly to restrict the outlet opening thereof, to form spaced stops for limiting the opening movements of a valve therein, and to form spaced crevices through 25 which fluid may escape from the valve-chamber, said crevices having their outer ends closed whereby to constrain the fluid passing therethrough to laterally enter the restricted outlet opening, and a valve mount- 20 ed in the valve-chamber.

In testimony whereof I have hereunto signed my name to this specification in the presence of two subscribing witnesses.

THOMAS A. DE VILBISS.
